(57) **CLAIM**

The ornamental design for a fluid dispenser, as shown and described.

DESCRIPTION

This Design Application is being filed concurrently with US Utility Application titled “Fluid Dispensing Assembly”; application Ser. No. 13/280,985; and inventors James Richards, Loren Brelje, and Michael Maher; the contents of which are hereby incorporated by reference.

FIG. 1 is a three-dimensional view of the fluid dispenser.

FIG. 2 is a front view of the fluid dispenser.

FIG. 3 is a back view of the fluid dispenser.

FIG. 4 is a side view of the fluid dispenser.

FIG. 5 is a side view of the fluid dispenser.

FIG. 6 is a top view of the fluid dispenser; and,

FIG. 7 is a bottom view of the fluid dispenser.

The broken lines in the drawings depict environmental subject matter and do not form a part of the claimed design.
